UNITED STATES PATENT OFFICE.

JOHN H. PENDLETON, OF BROOKLYN, AND CORNELIUS TIERS, ANDREW BRYSON, JR., AND LINCOLN MOSS, OF NEW YORK, ASSIGNORS TO THE RAPID TRANSIT CABLE COMPANY, OF NEW YORK, N. Y.

GRIP FOR CABLE RAILWAYS.

SPECIFICATION forming part of Letters Patent No. 404,499, dated June 4, 1889.

Application filed November 13, 1888. Serial No. 290,739. (No model.)

To all whom it may concern:

Be it known that we, JOHN H. PENDLETON, of Brooklyn, in the county of Kings and State of New York, and CORNELIUS TIERS, ANDREW BRYSON, Jr., and LINCOLN MOSS, all of the city and State of New York, have invented an Improvement in Grips for Cable Railways, of which the following is a specification.

Grips for cable railways have been made of two parts hinged together, the hinge being above the jaws, so that the jaws can be closed together in gripping the cable; but with gripping devices in which the jaws are rigid a very sudden strain is applied to the cable and the wire of the cable is rapidly injured and the grip worn out. Two endless belts have also been made use of, upon the surfaces of which are gripping-blocks, and the belts have been pressed one toward the other in gripping the cable.

In the application of C. Tiers, J. H. Pendleton, and A. Bryson, Jr., Serial No. 280,658, filed July 21, 1888, a single belt is represented, having upon its surface peculiarly-constructed gripping-blocks, and there is a shoe and lifter by which pressure is applied at one side of the cable to force the same against the blocks upon the endless belt, and in this connection the endless belt and the wheels for the same receive a movement from the cable by its action against guide-wheels, so that the belt is moving at the same speed, or nearly so, as the cable at the time the grip is brought into action.

In our present improvements we avail ourselves of this last-named feature, so that the endless belt is moving at the same or nearly the same speed as the cable when the grip is applied; but we apply the gripping-blocks in pairs upon the endless belt, so that the cable comes in contact only with the gripping-blocks, and these gripping-blocks are opened and closed by lateral pressure, so as to grasp the cable between them. By this improvement we are enabled to make use of only one endless belt or band, and to bring into contact with the cable nothing but the surfaces of the gripping-blocks, and these gripping-blocks are moving with the endless belt at the same speed,

or nearly so, as the cable, and in the same direction at the time the grip is applied. For this reason there will be little or no more wear upon either the cable or the gripping-blocks than there would be if the parts were at rest at the time the grip is applied, and in consequence of placing the gripping-blocks in pairs in two ranges upon one endless belt the gripping-blocks open automatically by the action of the belt as it tends to assume a straight and flat condition between one belt-wheel and the other, and in the gripping operation, as the pairs of blocks are brought up against the sides of the cable, the endless belt is bent to a trough or arch shape between one belt-wheel and the other, and in passing around the belt-wheels the pairs of gripping-blocks are always swung apart, so as to fully open the space between such pairs of blocks for the reception of the cable.

By these improvements the endless belt or band passes around the belt-wheels, and these belt-wheels are over the cable upon horizontal shafts instead of being in a horizontal or inclined position upon vertical or inclined shafts, as heretofore usual where two belts are made use of, and the cable is relieved from the friction and wear incidental to the use of a shoe-lifter to press the cable against the grip-blocks upon an endless belt where but one endless belt is employed.

In the drawings, Figure 1 is a general elevation of our improvements, with the platform-frame in section. Fig. 2 is a cross-section, in larger size, of the grip as open. Fig. 3 is a similar view of the grip as closed. Fig. 4 is a sectional plan at the line *x x* of Fig. 3. Fig. 5 is a vertical longitudinal section at the line *y y*, Fig. 2, of part of the belt. Fig. 6 is a cross-section of the car-platform and the devices for operating the grip. Fig. 7 is an inverted plan of part of the endless belt and of the gripping-jaws, partially in section; and Fig. 8 is a section of the devices for raising the cable, the view being endwise of such cable. Fig. 9 shows a modification of the devices for moving the grip-jaws.

A represents the platform of the car, or a portion thereof, such car being adapted

to travel upon either an elevated structure or upon a surface railway, our improvements, however, being especially adapted to elevated cable railways.

- 5   *a a* are the wheel-axles, and *a' a'* the wheels. Upon the under side of the platform A are the grooved guide-wheels B, secured in hanging brackets, and adjacent to the same is the lifter C, the lower end of which is formed as 10 a hook-shaped shoe, 2, that can pass beneath the cable, and the upper end of the lifter is linked to the lever-arm D, from which the link 3 extends to the hand-lever E, pivoted at 4 and provided with a pawl 5, acting against the stationary rack F; and there are lifters toward 15 the front and back ends of the platform A, and grooved guide-wheels, and the link 6 connects to the hand-lever E below the pivot 4, so that by moving this hand-lever E both the 20 lifters C are raised or lowered; and we provide cords or ropes 7, passing around pulleys, to a treadle 8, so that the lifters C can be drawn back and lowered and then swung by a spring *b*, or otherwise, until the shoes 2 pass 25 in beneath the cable G, and by moving the lever E the cable is raised bodily until it comes into contact with the grooved guide-wheels B. These guide-wheels B revolve freely, and hence they do not tend to set the 30 car in motion, and there is but little pressure or friction upon the shoes 2, as they should be smooth and of hardened steel, and in this position the cable is in a straight line, or nearly so, and adapted to being gripped by 35 the mechanism hereinafter described.
- Upon the platform A are the belt-wheels H H', with horizontal axles 10, and we prefer to make use of pulleys 11 on the axles 10 and endless belts 13 to pulleys upon the axles of 40 the grooved guide-wheels B, so that when these grooved guide-wheels B are revolved by contact with the cable the belt-wheels H H' are rotated gradually, but the belts 13 can slip upon the respective pulleys in the operation hereinafter described. The endless belt or band which we make use of passes 45 around the belt-wheels H H', and it is composed of a band K, of leather, thin steel plates, wire ropes, or other suitable materials, 50 and this band K may be of a single thickness or of two or more thicknesses, and the faces of the belt-wheels H H' are cylindrical; but the belt K is to be flexible, so as to pass freely around the said belt-wheels H H', and also to 55 allow for the said belt being bent up into the inverted trough shape, as seen in Fig. 3; and upon this endless belt are two ranges of grip-blocks in pairs, which are opened or moved apart, as shown in Fig. 2, to allow for the reception or discharge of the cable, or they are 60 pressed together, as shown in Fig. 3, to grasp the cable, and in so doing the straight part of the belt K is bent into the trough shape before referred to between the wheels H H'. 65 The grip-blocks L are preferably made of iron castings that are hollow, concave on their faces, and provided with ribs or flanges

20 on the edges. The bases 15 of the blocks are to be fastened to the endless belt K. We prefer, however, to introduce the filling plates 70 or layers 16, which are riveted to the bases 15 by rows of rivets 17, and the rivets or screws 18 connect the bases of the grip-blocks to the belt K near its edge, and these rivets also pass through the filling plates or layers 16, so 75 as to connect all the parts together.

The inner surfaces of the grip-blocks L are preferably of leather, made as layers or sections 19, packed closely between the flanges 20 of the grip-blocks L, and there are rivets 21 80 passing through the leather sections and through the flanges 20, so as to hold these leather sections firmly into the grip-blocks, and the leather sections project inwardly beyond the flanges 20 sufficiently to form durable wearing-surfaces, that are employed for gripping the cable; and these leather sections will last a long while before they are sufficiently worn away to allow the flanges 20 to 85 come into contact with the cable, and before 90 this happens the leather sections should be taken out and new ones inserted.

The grip-jaws M M' are pivoted together upon the longitudinal horizontal hinge 25, and it is preferable to make each grip-jaw in 95 two parts, bolted together by the bolts 26, so that the lower portions of the jaws, which are liable to injury, can be removed and replaced. In joining these two portions of the grip-jaws it is preferable to make a flange or rib at 28, 100 passing into a recess upon the other portion of the grip-jaw, and to introduce keys at 27, in addition to the bolts 26, for connecting the parts together and preventing end motion or a separation of the parts when in use. The 105 grip-jaws are supported by the hangers *a*², which have eyes surrounding the hinge-pin 25, and said hangers are bolted to the frame A. The inner faces of the grip-jaws are 110 grooved to correspond to the convex external portions of the grip-blocks L, and toward the ends of the grip-jaws they are beveled or made flaring, as seen in Fig. 7, so that the extreme ends of such grip-jaws are wider apart than the external surfaces of the grip-blocks as 115 they occupy the open position shown in Fig. 2, even after the grip-jaws may have been closed together into the position shown in Fig. 3. Thereby the grip-blocks will not come in 120 contact with any angle or obstruction as they slide in between the grip-jaws, as illustrated in Fig. 7.

Any suitable device may be made use of for swinging the grip-jaws upon the hinge or pivot 25. We, however, prefer to make use of 125 the lever-arms O, extending upward from the upper portions of the grip-jaws and provided with links O', that are pivoted to the upper ends of the lever-arms and joined together at 30 and to the vertical sliding rack-bar P; and 130 we have shown the pinions 31, fly-wheels Q, ratchet-wheel Q', and pawl 32 for moving and holding the rack-bar P and opening or closing the grip-jaws M M'.

It will now be understood that when the car is at rest the grip-jaws M M' are usually in an open position, as illustrated in Fig. 2, and the endless belt of grip-blocks is stationary. When the cable G is raised by the lifters C and the grooved guide-wheels B commence to revolve, the endless belt of grip-blocks is moved in the same direction as that of the cable at the place where the cable is between the grip-blocks L, and in order to prevent the cable being lifted too high we apply at intervals the pendent shields S, that take the place of sets or pairs of grip-blocks and prevent the cable being raised above the concave surfaces of the grip-blocks, as illustrated in Fig. 2. When the car is to be started, the fly-wheel Q and pinions are revolved and the rack-bar P' raised, so as to swing the lever-arms O outwardly and bring the jaws M M' toward each other. During this movement the grip-blocks L L' are also swung toward each other and come up at opposite sides of the cable, and in so doing the horizontal portion of the endless belt K, that is between the belt-wheels H H' and adjacent to the cable, is arched transversely and upwardly into the position shown in Fig. 3, and when the grip-blocks L come into contact with the sides of the cable they are moving at the same speed, or nearly so, as the cable, the convex exterior surfaces of the grip-blocks sliding freely upon the interior surfaces of the grip-jaws M M', and this movement is not interfered with by the ends of the grip-jaws M M', because such ends are beveled to allow the grip-blocks to enter between them freely; and it is to be understood that the leather sections 19 of the grip-blocks L grasp or adhere to the cable without injuring the same, and the leathers are not worn by the cable rapidly, because the leather sections and grip-blocks are moving with the cable as the grip is applied; but as the pressure of the grip-jaws is gradually increased the friction between the same and the exterior surfaces of the grip-blocks is increased, and the car itself receives motion from the grip and its movement is gradually accelerated until a maximum speed, corresponding to that of the cable, is obtained, when there will not be any slip between the grip-blocks and the grip-jaws, and the grip will hold firmly to the cable so long as the proper pressure is maintained of the grip-jaws upon the grip-blocks; but should it become necessary to lessen the speed of the car the wheel Q and pinions are turned back sufficient to lessen the pressure of the grip-jaws, so that the grip-blocks may slide more or less through between such grip-jaws, the endless belt K and wheels H H' revolving more or less with this movement, and when the grip-jaws are sufficiently opened the movement of the car may be arrested by brakes applied to the same, during which time the grip-blocks and endless belt are traveling freely along with the cable, and it is not necessary to open the grip-jaws M M' suf-

ficiently for dropping the cable, except at the ends of the route and when it may be necessary to pass from one track to another. 70

The concave faces of the grip-jaws M M' are exposed to wear from the contact therewith of the convex exterior surface of the grip-blocks, and should these jaws become too much worn or injured they can be replaced by removing the bolts 26, and it will be apparent that as the jaws M M' are brought toward each other and the relative positions of the grip-jaws and grip-blocks changed from that represented in Fig. 2 to that represented in Fig. 3, there is a slight turning movement of the one part in relation to the other until the lower surfaces of the bases 15 are brought into contact, or nearly so, with the flat upper faces of the grip-jaws above the concave surface thereof; hence the friction for holding the grip-blocks will be augmented when the lower surfaces of the bases 15 come into contact with the upper surface of the grip-jaws, and in consequence of the rivets or other connections 18 being near the outer edges of the bases 15 of the grip-blocks the endless belt K, of leather or other material, is free to assume an arched or trough-shaped condition, as seen in Fig. 3; but as soon as the pressure of the grip-jaws against the grip-blocks is relieved the pairs of grip-blocks will be swung apart, as the endless belt assumes a flat condition in approaching the belt-wheels H or H'. Thus the grip-blocks are self-acting, as they swing apart for relieving the hold upon the cable or for dropping the same.

As before mentioned, the belt K can be made of two or more layers and of any suitable material, and it is usually preferable to make use of longitudinal belts K' next to the belts K, and running either the whole length of such belts K or else running from one of the guide-blocks S to the next, in order that the grip-blocks L and the filling-pieces 16 may be more rigidly supported as they stand in the respective ranges, so as not to depend only upon the strength of the belt K for connecting the grip-blocks L in the ranges; and these belts K' become part of the endless belt K, and simply serve to more firmly connect the parts together and furnish the required strength at the proper places. Under some circumstances these grip-blocks L and the endless belt K, with which they are connected, may be made use of without the gripping-jaws M M', and in order to illustrate such use we have shown in Fig. 9 a right and left hand screw 40, with cylindrical nuts 41, applied to each pair of blocks and friction-wheels 42 43 at the respective ends of the screw-shafts 40 and stationary rails 44 45, with which such friction-wheels 42 and 43 may be brought into contact, so that as the car moves along or the belt is moved along by the cable the gripping-blocks can be tightened upon or loosened from said cable by rotating the right and left hand screw in either one di-

rection or the other, according to which of the bars or rails 44 45 is brought or comes into contact with the wheel 42 or 43.

We claim as our invention—

5 1. The combination, with the cable, of an endless belt, belt-wheels around which the belt travels, grip-blocks in pairs upon the endless belt adapted to swing apart for the reception or discharge of the cable, and mechanism for pressing the grip-blocks toward each other and at opposite sides of the cable, substantially as set forth.

15 2. The endless belt and belt-wheels around which the belt passes, in combination with grip-blocks connected to the endless belt, and sections of leather or similar material within the grip-blocks and recessed for the reception of the cable, and mechanism acting upon the grip-blocks for pressing them toward each other to grasp the cable, substantially as set forth.

25 3. The grip-blocks having convex exterior surfaces and sections of leather or similar material in their inner faces, in combination with grip-jaws grooved to fit the convex exterior surfaces of the grip-blocks and mechanism for acting upon the grip-jaws to move them toward or from each other and grasp the cable between the surface of the grip-

30 blocks, or to open such grip-blocks and allow the cable to drop, substantially as specified.

35 4. The grip-blocks L, formed as hollow castings with the bases 15, in combination with the sections or layers of leather or similar material introduced within the grip-blocks, the filling plates or layers 16, connected to the bases of the grip-blocks, and the endless belt K, to which the bases of the grip-blocks are fastened, substantially as set forth.

40 5. The combination, with the endless belt K and the wheels H H', of grip-blocks adapted to grasp the cable and provided with bases by which the grip-blocks are connected to the endless belt, and the pendent shields introduced at intervals and secured to the belt for preventing the cable being lifted too high and insuring the proper grasping of the cable as the grip-blocks are brought up at the sides thereof, substantially as set forth.

45 50 6. The combination, with the endless belt and the grip-blocks upon the same in pairs and adapted to receive the cable between them, of the grip-jaws having concave faces for acting against the grip-blocks, a pivot or hinge for connecting the grip-jaws together,

and levers for acting upon the grip-jaws to open or close the same, substantially as set forth.

7. The combination, with the grip-jaws and the hinge or pivot for connecting the same together, of levers for acting upon the grip-jaws, links, a rack and pinion for opening or closing the grip-jaws, an endless belt between the grip-jaws, and grip-blocks in pairs connected upon the belt and passing between the grip-jaws, substantially as and for the purposes set forth.

8. The combination, with the guide-wheels B, lifters C, and mechanism, substantially as specified, for moving the same, of the endless belt, and grip-blocks in pairs, and the belt-wheels around which the endless belt passes, and pulleys and an endless band for giving motion to the belt-wheels from the guide-wheel when the cable is brought into contact with the latter, substantially as set forth.

9. The combination, with the endless belt and grip-blocks connected thereon, of grip-jaws, a pivot or hinge for connecting the jaws together, such grip-jaws being made in two parts and bolted together to allow for the removal of the portions or jaws that act on the grip-blocks for repair or renewal, substantially as set forth.

10. The endless belt or band and the two ranges of grip-blocks in pairs upon such belt, in combination with the belt-wheels around which the endless belt passes, and a wheel receiving rotation from the cable, and a connection therefrom to the belt-wheels for giving to the belt and the two ranges of grip-blocks a motion in the same direction as the cable, substantially as set forth.

11. The combination, with the guide-wheel B, of a cable-lifter having a hook-shaped shoe 95 at the lower end, an actuating-lever and connections from the same to the lifter for raising and lowering the lifter, and a cord or connection for drawing the lifter aside as it is lowered, so that the shoe may pass in below 100 the cable, substantially as specified.

Signed this 10th day of November, 1888.
